Primary Examiner — Susan Bennett Hattan*Assistant Examiner* — Marie Fast Horse(74) *Attorney, Agent, or Firm* — Tarolli, Sundheim, Covell & Tummino LLP(57) **CLAIM**

We claim the ornamental design for a fan, as shown and described.

DESCRIPTION

FIG. 1 is a top plan view of a fan comprising a new, original and ornamental design;

FIG. 2 is a bottom plan view of the fan shown in FIG. 1;

FIG. 3 is a right side view of the fan;

FIG. 4 is a front side view of the fan;

FIG. 5 is a back view of the fan;

FIG. 6 is a left side view of the fan;

FIG. 7 is an exploded perspective view of the fan, as oriented in FIG. 1;

FIG. 8 is an exploded perspective view of the fan shown in FIG. 2; and,

FIG. 9 is another exploded perspective view of the fan as oriented in FIG. 2, showing internal structure for clarity of disclosure only.

The broken lines in the drawings depict a part of the fan that forms no part of the claimed design.
